CLAIM

The ornamental design for a toilet training chair, as
shown and described.

DESCRIPTION

FIG. 1 is an exploded perspective view taken from the
top front and right side of children's toilet training chair
showing my new design;

FIG. 2 is a rear elevational view thereof, showing the
urinal mounted on the side opposite that shown in FIG.
1;

FIG. 3 is a left side elevational view of FIG. 2; and
FIG. 4 is a top plan view of FIG. 2.

FIG. 2

FIG. 3

FIG. 4
